Claims priority, application Switzerland Nov. 10, 1960
5 Claims. (Cl. 181—64)

This invention relates to sound absorbing equipment for internal combustion engines and more particularly to mufflers or silencers which are attached to the exhaust pipe of such engines.

The subject of the invention is an improvement relating to a muffler or silencer as described in my Patent No. 2,818,132, dated December 31, 1957. In said patent a muffler or silencer is disclosed which is attached to the end of the exhaust pipe of an internal combustion engine, comprising duct means and a bucket wheel rotatably mounted in a chamber having inlet ports, connected to that duct means and an outlet port, communicating with an expansion chamber and outlet means from said expansion chamber to the atmosphere.

It is an object of the invention to provide for the silencing equipment a casing which is positioned and fastened in a housing. The casing walls being spaced from the walls of the housing and the housing is attached to the exhaust pipe of the engine.

Another object of the invention is to provide for the bladed wheel a bearing arrangement which is situated outside the casing, away from the flow of hot gas, in the space between the walls of the housing and the walls of the casing. The casing comprising flanges preventing exhaust gas to enter the space between the housing and casing walls.

Another object of the invention is to provide a hollow shaft for the bucket wheel. Cool air being drawn through the hollow shaft by suction means rotating with the bucket wheel. The air flowing through the hollow shaft prevents overheating of the bearing support arrangement.

Still another object of the invention is to provide for a fly wheel effect of the bucket wheel by the dimensioning of the hub thereof.

A constructional example of the invention is illustrated in the accompanying drawing, wherein:

FIG. 1 is a longitudinal vertical central section through the noise silencer or muffler according to the invention;

FIG. 2 is a plan view of the silencer without the outer tubular housing;

FIG. 3 is a cross-section along the line III—III in FIG. 1 and

FIG. 4 is a cross-section along the line IV—IV in FIG. 1.

Referring to the drawing, the silencer shown in FIGURES 1 to 4 is made up by a tubular housing or jacket 1 enclosing the silencer unit 10, 11, 12 and 36 shown in FIG. 2. The unit is of rectangular shape (see FIGURES 3 and 4) and positioned in the housing 1 by end plates 11 and 12 which prevent the gas to enter the chamber 31, see FIGURES 1 and 2. The casing with walls 10 is braced by traverses 24, 25, 26, 27, which permit to build the casing in two symmetrical halves which are firmly fastened to each other by said traverses. The joints of the two halves of the casing are covered by upper and lower plates and also by the end plates 11 and 12. The casing is screwed to the tubular housing 1 by means of a screw 9 engaging the threading of a boss 22 formed on the lower plate which covers the lower joint between the two halves of the casing 10.

In the casing 10 a bladed wheel 15 is mounted which is actuated by the exhaust gas of the motor to which the silencer housing 1 is mounted.

2

The exhaust gas from the motor enters the opening 29 in the casing 10. This opening communicates with two nozzle or guide passages 18 and which approach the turbine wheel on about diametrically disposed opposite 5 entrance openings 16 and 17 the flow of through 16 and 17 is so directed that the gas in both passages 18 and 20 rotate the blade wheel in the direction.

The guide ducts 18, 20, for the exhaust gas operating the bladed wheel and the enclosure of the wheel are 10 formed by the casing 10 and a suitably formed plate structure 28 as shown in the figures. The plate structure 28 is fixed to the casing 10 by means of the spacers 26 and 27. The structure 28 provides together with wall parts of the casing 10 two guide ducts 20 and 18. The guide ducts 20 and 18 receive the exhaust gas from the motor via the opening 29; 18 is the main guide duct, converging in flow direction from part of the opening 29 to the enclosure 13 of the bladed wheel 15, 15a and from there on continuing to the side of the outlet opening 23, where 15 it is formed by a partition member 33 adjacent the lower side of the outlet opening 23 by a 180° elbow 19. The member 33 is fastened to the casing wall by means of screws 30 and a spacer 32 which is secured to opposite casing walls. The gas from duct 18 enters into the 20 bladed wheel space through the opening 17 in the opposite direction to the direction of the exhaust from the motor. From the inlet opening 29 into the casing 10 up to the opening 17 of the duct 18 is made of a converging portion followed by a portion of constant cross-sections, as 25 shown in FIG. 1. The auxiliary guide duct 20 enters the space of the bladed wheel on the upper side thereof through the opening 16. The duct 20 converges from a part of the entrance opening 29 in the casing 10 up to the opening 16, it is however of smaller through flow cross-section and smaller length than the duct 18 and has no 30 portion of constant cross-section such as duct 18. The gas from the duct 20 impinges on the buckets 15a so as to rotate the bucket wheel 15 in the same direction as the gas in the ducts 18 and 19.

The bucket wheel 15 is mounted on a hollow shaft 14 of which both ends extend through the casing 10. 34 indicates the respective openings in the casing 10. The shaft 14 is supported outside of the casing 10 by means of ball bearings 35. The ball bearing supports consist of cuplike bearing covers 36 firmly fastened to the casing 10. Both covers 36 have a central bore hole 37 registering with the bore of the hollow shaft 14.

The hub 40 of the bucket wheel surrounds the shaft 14 and extends diametrically up to the free ends of the blading 15a. At the intersection of the pipe 38 with the central bore of the shaft 14 the pipe 38 has a cross-hole 39. At rotation of the bucket wheel cool air is drawn from the space 31 in the housing 1 and by centrifugal action blown through the pipe 38 providing for cooling of the 55 shaft and the bearings. The hub 40 of the bucket wheel is of a relatively large diameter to give it a great mass of inertia. The hub 40 and the blades 15a are also cooled by the cool air passing through the hollow shaft 14 and the pipe 38.

60 To prevent hot gas from the bucket wheel enclosure to escape into the bearing support 36 sealing rings 42 surround on both sides of the casing wall 10 the bore hole 34 for the shaft 14. The ring 42 on the inside of the casing 10 is placed into an annular recess in the hub 40 and on the outside of the casing 10 into a ring member 43.

The provision of low friction bearings and a great fly wheel effect of the bladed wheel is also useful with respect to the performance of the motor. By increasing the speed of the motor the rotational speed of the bladed wheel is 70 momentarily also increased, while at decreasing speed of the motor, due to the mass of inertia, the bucket wheel will not momentarily but only later, after the passage of

an interval of time decrease its rotational speed. Therefore if it is necessary for the driver of a car to decrease and at a short interval of time again increase the speed of the vehicle, the rotational speed of the bucket wheel will not change, therefore by its suction effect the density of the air charge in the motor will be increased during the period of deceleration of the motor and will support acceleration of the motor. This feature is of importance in the case with a car muffler according to the invention overtaking another.

I claim:

1. In a muffler, for use in connection with the exhaust pipe of an internal combustion engine, comprising in combination a housing defining on its interior a chamber and adapted to be connected with one end to said exhaust pipe, the chamber communicating with the outside air surrounding said housing, a casing disposed in said chamber having an inlet and an outlet for the exhaust gas and defining an enclosure, a bladed wheel rotatably mounted in said enclosure, duct means disposed in said casing and operable to conduct gases emanating from said exhaust pipe to said wheel, said duct means comprising a main duct including a one-half turn bend, an auxiliary duct having a cross-section smaller than of said main duct, both ducts receiving different amounts of gas from said gas inlet, both ducts terminating at said enclosure for said wheel at about diametrically opposite sides thereof, the gas in the ducts driving said wheel in the same direction, the gas in said main duct impinging on the blades of the wheel in a direction opposite to the exhaust direction, and the gas in said auxiliary duct impinging on the blades of the wheel in the exhaust direction, said gas being expelled from the enclosure of the wheel and to the outside of said casing through said outlet, a hollow shaft journaled outside said casing and extending through said enclosure and having an internal bore, a hub disposed in said enclosure and mounted on said hollow shaft and mounting said wheel, said hub being so dimensioned radially to provide for increased fly wheel effect of the wheel, bearing supports journaling said hollow shaft, said bearing supports being disposed in said chamber in the space intermediate said housing and said casing, sealing means operable to restrain the entry of exhaust gas from said enclosure into said chamber, and blower means connected to said hub and intercommunicating with the bore of said

hollow shaft and being actuatable to draw fresh air from said chamber through said bore and to expel the air centrifugally between the blades of the wheel into the interior of said enclosure.

5 2. A muffler according to claim 1, said blower means including said hub having between blades a hole extending radially, a pipe in said hole open at both ends and penetrating, and secured to, said hub and extending substantially up to the periphery of the free ends of adjacent 10 blades, said pipe having a cross-bore substantially in the middle of its length formed by the intersection with the bore of said hollow shaft, whereby at rotation of said wheel air is drawn through both ends of the bore of said hollow shaft and blown through and expelled at both ends 15 of said pipe for cooling said shaft and said bearing supports.

3. A muffler according to claim 1, said casing walls having openings for the penetration of said shaft and the hub extending up to said openings, an annular recess defined in said hub around said openings forming a slot 20 with the respective surface of the shaft, said sealing means including packing material in said slot operable to seal said openings against the escape of gas into said bearing support.

25 4. A muffler according to claim 3, said sealing means furthermore comprising on the outside of said casing and around said openings a container ring to position packing material to ensure the sealing of the openings.

5. A muffler according to claim 1, wherein said bearing supports comprise a cup-like support secured to the 30 wall of the casing on the outside thereof, low friction bearings supported and surrounded by said cup-like support, said support having a hole registering and intercommunicating with the bore of the hollow shaft for cooling 35 air to be drawn through said shaft.
